UNITED STATES PATENT OFFICE.

CAROLINE M. BROWN, OF MINNEAPOLIS, MINNESOTA, ASSIGNOR TO AUTOMATIC HEAT REGULATOR CO., OF ST. PAUL, MINNESOTA, A CORPORATION.

DAMPER.

1,136,209.

Specification of Letters Patent. Patented Apr. 20, 1915.

Application filed July 26, 1913. Serial No. 781,428.

To all whom it may concern:

Be it known that I, CAROLINE M. BROWN, a citizen of the United States, resident of Minneapolis, county of Hennepin, State of Minnesota, have invented certain new and useful Improvements in Dampers, of which the following is a specification.

My invention relates to dampers for smoke flues and the object of the invention is 10 to provide improved means for locking the damper to allow it to be set at any desired angle in the pipe.

A further object is to provide a mounting means for the damper which can be easily 15 and quickly applied to the wall of the pipe.

The invention consists generally in various constructions and combinations, all as hereinafter described and particularly pointed out in the claims.

20 In the accompanying drawings forming part of this specification, Figure 1 is a vertical sectional view of a pipe with my invention applied thereto, Fig. 2 is a transverse sectional view, Fig. 3 is a view, partially in section, illustrating the locking device, Fig. 4 is a detail sectional view of a modified construction, Fig. 5 is a detail sectional view, of Fig. 4.

In the drawing, 2 represents a pipe of 30 ordinary construction, having an opening 3 in its wall to receive a spindle 4 formed on one end of an arm 5. A damper blade 6 is secured to this spindle by a suitable means, such as bolts 7, said damper being prefer- 35 ably curved to conform substantially to the wall of the pipe and braced by means of a rod 7' extending across the damper blade and having looped ends fitting within holes in said blade. This construction allows the

40 blade to be made of thin material and when the rod 7 is put in place the blade may be bent to the desired degree of curvature and held in position by the rod. An ear 8 is secured to the wall of the pipe by suitable 45 means, such as rivets 9, and said ear has lugs 10 thereon to support a pivoted bolt 11 which passes through the arm 5. A weight 12 is adjustable back and forth on said arm and acts as a counter-balance for the blade 50 6. By means of this weight the blade may be balanced to hang at the desired angle in the pipe and when so adjusted the arm may be locked by a device which I will now describe in detail. The lower portion of the 55 ear has a part 12' pressed outwardly there-

from, forming a housing in the upper portion of which is a vertical slot 13. One side wall of the housing has an opening 14 therein. A bar 15 is arranged to slide in said housing and has a tongue 16 formed on its upper end fitting within a slot 13 and supported by the lower edge thereof. This bar is capable of vertical movement to raise said tongue into contact with the arm 5 or lower said tongue out of the path of said arm. 60 The bar is provided with a series of teeth 17 adapted to enter the hole 14 when said bar is swung toward that side of the housing. When the bar is moved in the opposite direction its tooth will be disengaged from the 65 housing and longitudinal movement of the bar in either direction will then be permitted either to lock or release the tilting arm. When the bar is moved upwardly to contact with the arm the damper blade will 70 be locked against further movement in one direction.

In Figs. 4 and 5 I have shown a modified construction, which consists in providing a lug 18 on the arm 5 and a sliding plate 19 80 having a slot 20 therein through which said arm is inserted into the pipe. This plate is preferably provided at its lower end with a finger grip 21 and the upper edge of the opening in the pipe is in position to engage 85 the lug 19 when the arm is swung to the point indicated in Fig. 4 and hold the damper blade in a vertical position against the wall of the pipe. The plate 19 has a limited sliding movement between the wall 90 of the pipe and the ear 22 in which an opening is provided to register with the opening in the plate and allow the insertion of the damper blade spindle.

The device may be made in various sizes, 95 according to the diameter of the pipe where it is to be used, and in various ways the details of construction may be modified and still be within the scope of my invention.

I claim as my invention:—

1. The combination, with a flue, of an arm pivoted thereon and provided with a spindle projecting into said flue, a counter-balance weight for said arm, a guide, a bar movable in said guide into the path of said arm and having means for engagement with said guide to hold said bar in different positions with respect to said arm and thereby vary the stroke of said arm, for the purpose specified. 105 110

2. The combination, with a flue, of an ear secured thereon and having an outwardly projecting portion forming a housing, said ear and the wall of said pipe having an opening therein, a weighted arm having a spindle projecting into said flue through said opening, a damper blade for said spindle, and a bar slideable in said housing and having means mounted for movement into the path of said arm.

3. The combination, with a flue, of an ear secured thereon, said ear and said flue having openings therein, an arm having a spindle fitting within said openings and projecting into said flue, a damper blade mounted on said spindle, said ear having a housing formed thereon provided with an opening in its side wall, a toothed bar slideable in said housing and having teeth adapted to enter said opening, said bar being mounted for movement into the path of said arm.

4. The combination, with a flue, of an arm pivoted thereon and provided with a spindle projecting into said flue, a damper blade mounted on said spindle, a counter-balance

weight for said arm, a sliding toothed bar, a guide therefor adapted to engage the teeth of said bar, said bar being mounted for movement into the path of said arm.

5. The combination, with a flue, of an arm pivoted thereon and having a part projecting within said flue and a weighted end extending outwardly from said flue, a damper blade having its middle portion secured to the inner end of said arm and composed of comparatively thin, flexible material, and a rod bridging the middle portion of said blade and having hooked ends to enter holes in the end portions of said plate for holding said end portions in their curved relation with respect to the middle portion of said blade, said end portions being curved to conform to the curvature of the wall of the flue.

In witness whereof I have hereunto set my hand this 14th day of July, 1913.

CAROLINE M. BROWN.
